UNITED STATES PATENT OFFICE.

URIAH F. McBURNEY, OF BOISE, IDAHO, ASSIGNOR OF FIFTY-FIVE ONE-HUNDREDTHS TO ALFRED W. WICHER, OF BOISE, IDAHO.

HEAD-GATE.

No. 828,233.

Specification of Letters Patent.

Patented Aug. 7, 1906.

Application filed October 19, 1905. Serial No. 283,432.

To all whom it may concern:

Be it known that I, URIAH F. McBURNEY, a citizen of the United States, and a resident of Boise, in the county of Ada and State of Idaho, have invented a new and Improved Head-Gate, of which the following is a full, clear, and exact description.

The purpose of the invention is to provide a simple, durable, and economic portable head-gate adapted to be used in open ditches or laterals and which can be adjusted to any shape or size of ditch within predetermined dimensions.

A further purpose of the invention is to provide the head-gate with a waste-gate that will allow any water to pass which may be needed farther down the lateral and to so locate the said waste-gate that no water passing through the waste-gate will wash around the main gate.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the head-gate applied to a ditch. Fig. 2 is an enlarged front elevation of the gate, showing one section adjustable upon the other. Fig. 3 is a vertical section through the gate, taken practically on the line 3-3 of Fig. 2; and Fig. 4 is a front elevation of the rear or fixed section of the gate drawn upon a smaller scale.

The device consists, primarily, of two main members A and B, which are in plate form and lie one upon the other, the member A being the rear member, and is adapted to be fixed in the ground, while the member B, which is the forward member, is adapted to have sliding and pivotal movement on the rear or fixed member A. The rear member

A is provided with a recess 10 in its right-hand edge, and the longitudinal wall 11 of this recess is inclined from the top downward to the bottom wall in direction of the left-hand side of the said member A, as is shown in Fig. 4, and also the bottom wall of the recess 10 at its right-hand portion is provided with a downwardly and outwardly extending section 12, as is also shown in Fig. 4.

A post 13 is made fast to the longitudinal central portion of the rear member A, extending above and below the said member, and the lower end 14 of the post 13 is pointed, so that it may readily enter the ground. Preferably the lower edges of both of the members A and B are rounded off at their corners, so that this portion of the device also may be readily forced into the ground, as is shown in Fig. 3.

The two sections A and B are substantially of the same width and length, and the outer or movable section B is provided at the top with a transverse curved slot 15, extending nearly from side to side, and at its bottom central portion the said outer section B is provided with a straight transverse slot 16. A pivot-bolt 17 is passed through said slot 16 and through the post 13, being provided at the rear with a suitable nut 17^a, and at the upper right-hand corner of the back section A a bolt 18 is passed through said section and through the slot 15 at the upper end of the forward section B, the bolt 18 having a suitable nut 18^a at its rear end. Thus it will be observed that the outer section B has pivotal connection with the rear section A, the latter section being adapted to be fixed in the ground, and also that the said forward section B has horizontal sliding movement on the rear section, enabling the head-gate to be adapted to different sizes and shapes of ditches or laterals.

An opening B' is made in the outer member B at the left-hand side of the center of said member, as is shown in Figs. 2 and 3, and at the side and bottom marginal portions of this opening sideways 19 are produced. In said sideways 19 a waste-gate 20 has guided movement, being capable of closing the opening B' and of uncovering it to a greater or lesser extent. The said waste-gate 20 is provided at the top with a suitable handle 21, whereby it may be readily operated.

When the two members A and B are brought in substantially exact registry one with the other, the opening B' is cut off more or less at its left-hand side by reason of the inclined wall 11 of the recess 10 in the rear member A; but when the forward member B is slid to the right the opening B' will be less obstructed or entirely free throughout its length and breadth, as may be de-

sired. In the event it is necessary to give the outer member B an inclination in direction of the right-hand side of the device in order to properly fit the head-gate to the 5 ditch or lateral the formation of the recess 10 will at such time permit the opening B' to be entirely unobstructed except by the waste-gate 20, which is used to regulate the amount of water to be passed from the ditch at which 10 the head-gate is located, and by placing the waste-gate at one side of the center of the device it is evident that when the water passes through the opening B' it will not have a tendency to work around the gate 15 proper or disturb its position in the earth.

A horizontal tongue 14^a is located at the rear lower portion of the post 13, and this tongue engages with the bottom of the ditch when the head-gate is in position, regulating 20 the extent to which its lower portion shall be extended into the earth.

Having thus described my invention, I claim as new and desire to secure by Letters Patent—

- 25 1. In a head-gate, a member having a recess in one side and a second member having pivotal and sliding movement on the recessed member, the said second member being provided with a waste-gate.
- 30 2. In a head-gate, a fixed member having a recess in one side, an outer member having a pivotal and sliding movement on the fixed member, the said outer member being pro-

vided with a waste-gate, and means for holding said member in adjusted position.

3. In a head-gate, a rear and a forward member, means for securing the rear member in the ground, the forward member being mounted for pivotal and horizontal sliding movement on the rear member, the said forward member being provided with an opening at one side of its center, and a waste-gate for said opening.

4. In a head-gate, the combination with a rear member and a post secured thereto and adapted to enter the ground, the said rear member being provided with a recess at its right-hand edge, the longitudinal wall of which opening is inclined, of a forward member having a curved slot at its upper portion 50 and a straight slot at its lower central portion, pivot-bolts carried by the rear member, which pass through the said slots, means for tightening the said bolts, the said forward member being provided with an opening to 55 the right of its center and sideways at the sides and bottom of the opening, and a waste-gate adapted to the said sideways, to open or to close the said opening, as described.

In testimony whereof I have signed my 60 name to this specification in the presence of two subscribing witnesses.

URIAH F. McBURNEY.
